UNITED STATES PATENT OFFICE.

HENRY BENJAMIN LIGHT, OF SAN QUENTIN, CALIFORNIA, ASSIGNOR OF ONE-HALF
TO CHARLES ALLEN ALMY, OF SAN QUENTIN, CALIFORNIA.

HEEL.

Application filed January 14, 1922, Serial No. 529,390. Renewed July 31, 1923.

To all whom it may concern:

Be it known that I, HENRY BENJAMIN LIGHT, a citizen of the United States, residing at San Quentin, in the county of Marin and State of California, have invented new and useful Improvements in Heels, of which the following is a specification.

This invention relates to improvements in spring heels for shoes and has for an object the provision of a metallic heel which may be secured to a shoe to provide a cushion.

Another object of the invention is the provision of a heel of the above character which is formed of separate sections, connected together in a manner to permit of relative vertical movement and normally held in extended position by a spring, the latter being of novel formation and being removably arranged within the heel, whereby a spring of proper resiliency for the wearer, may be provided.

Another object of the invention is the provision of a metallic shoe heel, to which may be secured a compressible lift of suitable material, to further add to the comfort of the wearer and prevent undue noise when in use.

With the above and other objects in view, the invention further includes the following novel features and details of construction, to be hereinafter more fully described, illustrated in the accompanying drawings and pointed out in the appended claims.

In the drawings:—

Figure 1 is a perspective view of a shoe with the heel applied.

Figure 2 is an enlarged vertical longitudinal sectional view through the heel portion of the shoe.

Figure 3 is a detail perspective view of the rigid section of the heel.

Figure 4 is a similar view of the yieldable section with the spring in position.

Figure 5 is a detail view of the spring.

Referring in detail to the drawings, wherein like characters of reference denote corresponding parts, the reference character 10 indicates a shoe, while the improved heel which constitutes the present invention is indicated generally at 11.

This heel is of a metallic structure and comprises a section 12 which is adapted to be

secured to the shoe and a section 13, which 55 is carried by the section 12 and is movable relatively thereto.

The section 12 which is rigid with the shoe, includes an attaching plate 14 which is provided with a plurality of openings 15, for the passage of suitable fastening devices, by means of which the section 12 is secured in place. Extending around the edge of the plate 14 is a right angularly disposed flange 16, which is adapted to telescopically 60 engage a similar flange 17 which extends from a plate 18 of the movable section. Extending from the flange 17 of the section 13 are lugs or projections 19, which are preferably formed by being struck up from the 65 metal of which the heel is formed and these lugs or projections 19 are adapted to be received within elongated sockets 20 which extend transversely of the flange 16 of the section 12. The relative lengths of the lugs 70 or projections 19 and the sockets 20 are such that limited vertical movement will be permitted of the section 13, with respect to the section 12, but accidental separation of the sections will be prevented. If desired, 75 the section 13 may have secured thereto by means of nails or similar fastening devices, a compressible lift 21, which may be formed of leather or any other suitable material.

Located within the section 13 is a spring 80 which engages the section 12 and acts to hold the said sections normally in extended position. This spring comprises a pair of upwardly and inwardly extending spring arms 22, which are carried by a plate 23, 85 the latter being of a size and shape to snugly fit within the section 13, so that the spring will be all times held in proper position. This also permits of the removal and substitution of springs of different tension, so 90 that the character of the spring may be properly adapted for use to the weight of the particular person wearing the heels. This permits of the heels being manufactured and sold independent of the shoes, so 95 that the springs may be stamped or otherwise classified as to their particular resiliency and a person using the heels may purchase springs suitably adapted to his weight.

The invention is susceptible of various 100 changes in its form, proportions and minor details of construction and the right is herein reserved to make such changes as properly

fall within the scope of the appended claims.

Having described the invention what is claimed is:—

- 5 1. A shoe heel comprising a rigid section adapted to be secured to a shoe, a movable section, means for securing the movable section to the rigid section in a manner to permit of relative vertical movement and a yieldable element located between the sections, said element comprising a plate removably fitting within one of said sections and spring arms carried by the plate and extending inwardly and spaced from the latter for contact with the other section.
- 10 2. A shoe heel comprising a rigid section adapted to be secured to a shoe and including an attaching plate and right angularly disposed flanges extending from the attaching plate, a yieldable section also including an attaching plate and right angularly disposed flanges extending from said plate and
- 15 20

adapted to telescopically engage the flanges of the rigid section to permit of sliding movement, means for limiting said movement, a plate shaped to conform to the shape of the heel and located within and having its edges engaging the flanges of one section, inwardly extending spring arms located at opposite edges of and having their free ends spaced from the plate for contact with the other section.

3. A shoe heel comprising a rigid section and a movable section telescopically connected to permit of relative sliding movement, means for limiting said movement and a spring positioned between said members, said spring comprising upwardly and inwardly extending spring arms and a positioning plate connecting the arms.

In testimony whereof I affix my signature. 40

HENRY BENJAMIN LIGHT.
